UNITED STATES PATENT OFFICE.

AXEL ANDERSON, OF ST. PAUL, MINNESOTA, ASSIGNOR TO RUSSELL GRADER MANUFACTURING CO., OF MINNEAPOLIS, MINNESOTA, A CORPORATION.

STEERING DEVICE.

1,256,283.

Specification of Letters Patent. Patented Feb. 12, 1918.

Application filed June 12, 1915. Serial No. 33,711.

To all whom it may concern:

Be it known that I, AXEL ANDERSON, citizen of the United States, resident of St. Paul, county of Ramsey, State of Minnesota, have invented certain new and useful Improvements in Steering Devices, of which the following is a specification.

My invention relates to a steering mechanism by means of which a grader or other machine can be operated out of alignment with its motive power or in a direction parallel therewith.

The principal object of the invention is to provide a steering mechanism within control of a person on the machine for shifting the angle of the draft pole without stopping the machine.

Other objects of the invention will appear from the following detailed description.

The invention consists generally in various constructions and combinations, all as hereinafter described and particularly pointed out in the claims.

In the accompanying drawings forming part of this specification,

Figure 1 is a side elevation of a grading machine with my invention applied thereto,

Fig. 2 is a front view with the pole removed,

Fig. 3 is a horizontal sectional view through the forward portion of the machine, illustrating the manner of attaching the pole to the axle,

Fig. 4 is a transverse sectional view through the pole and the screw and worm shifting mechanism thereon,

Fig. 5 is a detail view, showing the manner of mounting the worm and worm wheel on the pole.

In the embodiment of the invention shown in the drawings, 2 represents the frame of the grader, having axles 3 and 3^a, and carrying the wheels 4 and 4^a. A yoke 5 is preferably mounted on the horizontal

axle 3, is arched over the middle portion of the same, and is provided with a plate 6 seated on the middle portion of the yoke and having its ends overhanging brackets 7 that are secured to the axle and the ends of the

yoke. A rocker 8 is supported on the arched middle portion of the yoke 5 and a king-bolt 9 passes down through the forward portion of the frame 2 and through the rocker and yoke and is seated on the axle.

A plate 10 is preferably interposed between

the yoke and rocker and has a hole therein through which the king-bolt passes. This plate is provided with loops 11 to receive a T-head 12 on which the tongue 13 is secured. The plate 10 is free to swing with the tongue 13 to any desired angle with respect to the forward axle and through this plate the draft on the tongue is transmitted to the king-bolt. A clamp 14 is secured by suitable means, such as a bolt 15, to the draft tongue and has a bracket 16 provided with bearings 17 for the rod 18 that is splined in a worm 19 between the bearings 17. When, therefore, the rod 18 is revolved, the worm will be revolved also, while the rod is free to slide lengthwise in the worm independent of its revolving movement.

The tongue 13 is preferably made of tubing having a telescoping section 20 at its outer end that is adjustable lengthwise with respect to the main portion of the tongue by means of a bolt 21 fitting holes 22 and 23 in the tongue and extension. The upper portion of the clamp 14 has a stud 24 thereon whereon a worm gear 25 is mounted, its teeth meshing with the worm 19. Upon this worm gear a sheave 26 is mounted, preferably integral with the gear, its upper surface being preferably flush substantially with the top of the stud and secured thereon by suitable means, as the screw 27 and washer 28. The face of the sheave 26 has lugs 29 thereon to engage the links of a chain 30 which passes around the sheave and has its ends attached to rods 31 pivotally connected to bolts 32 mounted in the brackets and the plate 6. These rods and their flexible connections, engaging the lugs of the sheave 26, operate to hold the forward axle parallel with the rear axle and compel the wheels to run in a direction parallel with the line of draft of the machine but in staggered relation with respect thereto. Turn buckles 33 are preferably mounted in the rods 31 to take up the slack in the chain and obtain the desired degree of tension between the sheave 26 and the connections of the rods 31 with the axle. The rear end of the rod 18 has a coupling 34 connecting it to a rod 35 which has bearings in a bracket 36 and is coupled to a steering rod 37 extending to the rear portion of the machine and provided with a suitable steering wheel 38 within convenient reach of the operator of the machine standing upon a plat-

form 39. The bracket 36 is loosely mounted on the king-bolt to allow it to oscillate horizontally and accommodate itself and the steering rod to the different positions of the 5 wheels.

The forward end of the tongue has a clevis 40 for connection with a suitable motive power device, such as a traction engine, it often being desired to run the scraper over a 10 surface parallel with the direction of movement of the tractor and out of alignment therewith, and by means of this tongue the driver of the machine can shift the pull from side to side of the center of the axle 15 and maintain any desired angle between the forward axle and the tongue in guiding the machine, it being understood, of course, that wherever adjusted, the tongue will be locked by the worm and gear wheel and their connection with the forward axle. 20

I have shown this invention applied to a grading machine having a suitable scraper blade 40 supported by the machine frame between the forward and rear axles, but it 25 will be understood to be applicable to other machines where it is desired to operate them in an offset or staggered relation with respect to the motive power.

The details of the construction may be 30 varied in many particulars without departing from my invention.

I claim as my invention:

1. The combination, with a machine frame

having forward and rear axles and carrying 35 wheels, of a yoke mounted on the forward axle, a rocker supported by said yoke, a plate seated on said rocker, brackets mounted on said axle beneath said plate, a king-bolt passing through said rocker and yoke, a draft tongue pivotally connected with 40 said king-bolt, flexible means connected with said plate and brackets on opposite sides of said king-bolt, means mounted on said tongue and engaging said flexible means for swinging said tongue horizontally to change 45 the direction of draft thereof and locking it at any desired angle with respect to said axle.

2. The combination with a machine frame 50 having forward and rear axles and carrying wheels, of a draft tongue having a pivotal connection with the forward axle, a plate supported by said axle and having its ends extending in proximity to the forward carrying wheels, means supporting the ends of 55 said plate, flexible means connected with said plate on opposite sides of its center, and means mounted on said tongue and engaging said flexible means for swinging said tongue horizontally to change the direction 60 of draft thereof and locking it at any desired angle with respect to said axle.

In witness whereof, I have hereunto set my hand this 31st day of May, 1915.

AXEL ANDERSON.
